UNITED STATES PATENT OFFICE.

LEROY BAUMGARTL, OF CHICAGO, ILLINOIS, ASSIGNOR TO FEDERAL CEMENT TILE COMPANY, OF CHICAGO, ILLINOIS, A CORPORATION OF ILLINOIS.

BUILDING SLAB OR TILE.

1,203,170.

Specification of Letters Patent.

Patented Oct. 31, 1916.

Application filed February 1, 1916. Serial No. 75,527.

To all whom it may concern:

Be it known that I, LEROY BAUMGARTL, a citizen of the United States, residing at Chicago, in the county of Cook and State of Illinois, have invented a new and useful Improvement in Building Slabs or Tile, of which the following is a specification.

My invention relates to improvements in slabs of concrete, clay, or the like substances, 10 which are used for forming walls, floors, ceilings, roofs and the like; and more particularly to slabs of the kind which are provided with cells, or chambers, opening through edges of the slabs, or tile, at which 18 edges they interfit with adjacent slabs, or tile, when positioned for use.

As is well understood in the art, the cells, or chambers, are provided in the slabs, or tile, primarily for the purpose of insulating 20 the air at one side of the slabs, or tile, from heat or cold at the opposite side of the slabs, or tile, as for example where the slabs, or tile, form a roof-structure and it is desired to insulate the air in the space beneath the 25 roof against the hot or cold air outside of the building. Furthermore, it is desired that the joints between the slabs, or tile, be sealed not only against passage of air therethrough from one side to the other of the 30 structure formed of the slabs, or tile, but also against entrance of air and moisture from the exterior of the slabs, or tile, into the cells, or chambers thereof, and the entrance into these cells, or chambers, of air 35 from the inner sides of the slabs, or tile.

As slabs, or tile, have hitherto been constructed, considerable difficulty has been experienced in properly sealing the joints between them; a relatively great amount of 40 sealing material is required and objectionable squeezing of the sealing material through the lower part of the joints results, producing an uneven under surface to the structure and oftentimes littering the floor 45 beneath by the squeezed-out material.

My object is to provide for the proper sealing of the joints between slabs, or tile, of the character above set forth, by the use of the minimum amount of sealing material, 50 and without the above-referred to objection of squeezing the material out of the joints.

Referring to the accompanying drawing:— Figure 1 is a face view of a slab constructed in accordance with my invention, the central 55 portion thereof being broken away; Fig. 2,

an edge view of the slab of Fig. 1, the edge shown being the one through which the cells, or chambers, of the slab open; and Fig. 3, a perspective sectional view of two similar slabs showing the manner of joining them together in accordance with my invention, the section being taken at a line corresponding to the line 3 of Fig. 1 and viewed in the direction of the arrow.

The particular form of slab illustrated, and in which I have chosen to illustrate my invention, is formed with a plurality of cells, or chambers, indicated at 4, and separated by partitions 5, these cells opening through an edge of the slab. The opposite edge of the slab is preferably provided with a flange, or bead, 6, which extends lengthwise thereof throughout the full length of the latter, this bead being located intermediate the upper and lower surfaces of the slab and preferably in line with the cells 4, as represented. The edge of the slab provided with the bead 6 contains a groove, or recess, 7, which extends, by preference, the full length of the slab below the bead 6, and the ends of the partitions 5 and the end-walls 8 of the slab, at the opposite edge of the latter are shaped to conform, generally, to the contour of the bead.

In building a structure from the slabs, the latter are interfitted with each other as shown, by way of example, in Fig. 3, the beaded edges of the slabs opposing the edges thereof through which the cells, or chambers, 4, open, in which condition the beads 6 oppose the concaved ends of the partitions 5 and walls 8, as shown. Preliminary to thus assembling the slabs, cement, such as elastic cement, or any other suitable sealing material is placed in the recess 7 in sufficient amount to cause the corner edges 9 of the slabs, which directly oppose the adjacent recesses 7, to become embedded in the cement represented at 10, and squeeze it in opposite directions, as represented, thus producing a highly effective seal against air entering the cells, or chambers, from the lower sides of the slabs. The sealing of the upper portions of the joints between adjacent slabs, above the cells 4, may be effected in any desirable manner, as by applying thereto cement, as represented at 11.

It will be understood that by constructing slabs, or tile, in accordance with my invention, a highly effective joint is obtained with

the use of a relatively small amount of sealing material, and squeezing of the latter through the joints at the under side of the structure is prevented.

5 What I claim as new, and desire to secure by Letters Patent, is:—

A hollow slab or tile open at one edge and provided with cell-forming partitions the outer ends of which are concaved, the said

10 slab or tile being closed at its opposite edge and provided thereat with a convex portion extending along the same to fit in the

open end of an abutting tile when multiples of said tiles are arranged in edge relation, said closed edge of the tile being also provided with a recess flanking said convex portion and inset relative thereto to receive sealing material and into which recess one of the edges of the open end of the tile enters, whereby such open end is sealed.

15 LEROY BAUMGARTL.
